US00D931484S

(12) **United States Design Patent** (10) **Patent No.:** **US D931,484 S**
Zhao (45) **Date of Patent:** **** Sep. 21, 2021**

(54) **COMBINED LEG AND FOOT MASSAGE DEVICE**

(71) Applicant: **Xiamen High Top Electronic Technology Co., Ltd.**, Fujian (CN)

(72) Inventor: **Liangsan Zhao**, Fujian (CN)

(**) Term: **15 Years**

(21) Appl. No.: **29/706,247**

(22) Filed: **Sep. 19, 2019**

(51) **LOC (13) Cl.** **28-03**

(52) **U.S. Cl.**

USPC **D24/213**

(58) **Field of Classification Search**

USPC D24/188, 189, 190, 200, 211, 212, 213, D24/214, 215; D29/101.1

CPC A61H 1/00; A61H 2023/002; A61H 2201/1238; A61H 7/002; A61H 7/007

(57) **CLAIM**

The ornamental design for a combined leg and foot massage device, as shown and described.

DESCRIPTION

FIG. 1 is a front elevational view of a combined leg and foot massage device showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is another perspective view thereof.

1 Claim, 8 Drawing Sheets
